JOSEPH N. B. BOND, OF NEW YORK, N. Y.

Letters Patent No. 74,883, dated February 25, 1868.

IMPROVEMENT IN BOILER-FEED LOW-WATER DETECTOR.

The Schedule referred to in these Letters Patent and making part of the same.

TO ALL WHOM IT MAY CONCERN:

Be it known that I, JOSEPH N. B. BOND, of 19 Seventh avenue, New York city, in the county and State of New York, have invented a new and useful Improved Low-Water Detector and Boiler-Feed; and I do hereby declare that the following is a full, clear, and exact description thereof, which will enable those skilled in the art to make and use the same, reference being had to the accompanying drawing, which represents a sectional front elevation of this invention.

This invention relates to a low-water detector, the operation of which depends upon a buckling-tube, which is situated at the level of the mean water-line of the boiler, and connects at one end with the steam-space, and at the opposite end with the water-space of said boiler, while its centre is connected to a lever, which acts on the stop-valve of an alarm-whistle in such a manner that when the water in the boiler sinks below the mean water-line, and the tube is caused to expand and buckle up by the heat of the steam passing through it, the stop-valve of the alarm-whistle is caused to open automatically, and the alarm is sounded. As soon as this takes place the engineer or fireman opens a stop-cock, which admits steam from the boiler to a tank, which connects with the hydrant or with a suitable water-reservoir, and with the water-space of the boiler. If this steam-cock is closed, the water enters the tank first through a conical nozzle, and after the steam in said tank has condensed, through a cylindrical pipe, until the stop-cock in the supply-pipe is closed by the action of a float in the tank. When the water in the boiler gets low, the steam-cock is opened, the pressure in the tank becomes equal to the boiler-pressure, and the water contained in the tank sinks down into the boiler by its own gravity.

A represents a steam-boiler, with its try-cocks *a b c*, the middle cock, *b*, indicating the mean water-line of the boiler. On a level with this mean water-line is situated the buckling-tube *B*, the ends of which are secured in rigid sockets, *C C'*, so that if the tube expands it is compelled to buckle up. One end of said tube connects by a pipe, *d*, with the steam-space of the boiler, and its other end connects by a pipe, *e*, with the water-space, so that when the water in the boiler rises to or above the mean water-line, the buckling-tube is filled with water; but when the water in the boiler sinks down below the mean water-line, the buckling-tube fills with steam. The tube *B* connects at about the middle of its length by a strap, *f*, with a lever, *D*, which acts on the stop-valve, *E*, of an alarm-whistle, *F*. When the water in the boiler sinks below the mean water-line, so that the tube *B* fills with steam and buckles up by the increased temperature, the lever *D* opens the stop-valve *E*, and the alarm is sounded.

In order to enable the engineer or fireman to inject water in his boiler as soon as the alarm-whistle is blown, I have applied a tank, *G*, which connects by a pipe, *g*, with the steam-space, and by a pipe, *h*, with the water-space of the boiler, and by a pipe, *i*, with a hydrant or water-reservoir, situated at such a height that the water will enter the tank under a certain pressure or head. The pipe *g* is opened and closed by a stop-cock, *j*, and the pipe *h* is provided with a check-valve, *k*, which prevents the water from the boiler passing up into the tank *G*. The pipe *i* extends into the tank, and it is furnished with a stop-cock, *l*, which is opened and closed by the action of a float, *H*. Beyond the stop-cock said pipe *i* branches off into a conical nozzle, *m*, and a cylindrical nozzle, *n*, which latter is provided with a check-valve, *o*. If the steam-cock *j* is closed, after the tank *G* has been emptied, the water rushes in first through the conical nozzle *m*, against the pressure of the steam still remaining in the tank, and as this steam condenses, the check-valve *o* opens and the water enters also through the cylindrical nozzle *n*, until it rises to such a height that the stop-cock *l* will be closed by the action of the float *H*, which float is adjusted so that the water is not permitted to fill up the tank, and that in the upper part thereof a certain space is left for the steam, and that the steam, on being admitted to the tank, will act immediately upon the entire surface of the water contained therein. When the alarm-whistle sounds, the engineer opens the steam-cock *j*, and the water in the tank descends into the boiler by its own gravity. After the tank has been emptied, the steam-cock is closed, and the tank fills again automatically, as above described.

In such places where the water has to be taken from a well, a branch pipe, *p*, is made to extend down into the well from the pipe *h*, and the pipe *i* is dispensed with. The pipe *p* is provided with a stop-cock, *q*. When it is desired to fill the tank, the stop-cock *q* is opened, and the steam contained in the tank blows off into the well, where it condenses, and by these means a vacuum is formed in the tank, and the water rushes into the same

by the action of the atmospheric pressure. After the tank has thus been filled the stop-cock *q* is closed, and the steam-cock *j* is opened, and the water descends from the tank into the boiler by its own gravity. If desired, the steam-cock *j* can be connected to and operated automatically by the buckling-tube *B*. By these means an automatic alarm and boiler-feed are obtained whereby the engineer is enabled to supply any deficiency of water in the boiler whenever it is requisite.

What I claim as new, and desire to secure by Letters Patent, is—

1. The buckling-tube *B*, operating the alarm-whistle *F* by means of the arms *Df*, and connected with the boiler *A*, as shown, when arranged and operating as herein set forth and shown.
2. The float *H*, operating the valve *l*, in the conical nozzle of the supply-pipe *i*, which is provided with the nozzle *n* and check-valve *o*, in combination with the pipes *h p*, steam-cock *j*, and buckling-tube *B*, substantially as and for the purposes described.

JOSEPH N. B. BOND.
